UNITED STATES PATENT OFFICE

153,733

DESIGN FOR A FLASHLIGHT

Earl L. Schofield, Rockford, Ill., assignor to Burgess Battery Company, Freeport, Ill., a corporation of Delaware

Application December 26, 1947, Serial No. 143,349

Term of patent 14 years

(Cl. D48—25)

To all whom it may concern:

Be it known that I, Earl L. Schofield, a citizen of the United States, residing at Rockford, in the county of Winnebago and State of Illinois, have invented a new, original, and ornamental Design for a Flashlight, of which the following is a specification, reference being had to the accompanying drawing, forming part thereof.

Fig. 1 is a side view of a flashlight, showing my new design;

Fig. 2 is a right end view;

Fig. 3 is a top view, and

Fig. 4 is a left end view.

The dominant characteristic of my design resides in the portions shown in full lines.

I claim:

The ornamental design for a flashlight, as shown and described.

EARL L. SCHOFIELD.
